EASY OPENING SHEET METAL CONTAINER

William F. Punte, Syracuse, N. Y., assignor to
 Continental Can Company, Inc., New York,
 N. Y., a corporation of New York

Application January 28, 1937, Serial No. 122,851

3 Claims. (Cl. 220—27)

The invention relates to new and useful improvements in an easy opening sheet metal container wherein the metal is ruptured for providing an opening into the container.

5 It is the usual practice to thin the metal by scoring so that the metal may be easily ruptured by a force applied thereto at right angles to the plane of the metal. Other ways have also been suggested for the thinning of the metal, but in 10 each instance, the metal may be ruptured by forces applied internally of the container as well as externally thereof.

An object of the present invention is to construct a container wherein the metal is thinned so that it may be easily opened by pressure applied externally to the thinned section of the metal, and wherein the thinned section is so related to the metal wall containing the same that the same pressure or a greater pressure applied 20 internally against the thinned section of the metal will not rupture the same.

A further object of the invention is to provide an easy opening container of the above type which is shaped so as to provide a shoulder which is so related to the thinned section that a lever opener may be engaged with said shoulder and pressed against the thinned section for the rupturing of the metal.

In the drawings—

30 Figure 1 is a view showing in vertical section a container for beverages to which the invention has been applied;

Fig. 2 is an enlarged sectional view through one side of the nozzle portion of the container;

35 Fig. 3 is a view similar to Fig. 2, but showing in broken lines the position of the thinned portion at the angle where pressure has been applied to the bottom wall almost to the point of rupturing the metal, and in full lines the metal after it is ruptured;

40 Fig. 4 is a view showing the nozzle portion of the container and with an opening lever applied thereto preparatory to exerting a pressure on the bottom wall of the depression for rupturing the metal;

45 Fig. 5 is a view showing applicant's improvement as applied to a container end wherein a section of the metal adjacent one side of the end is thinned for rupturing;

50 Fig. 6 is an enlarged sectional view of a portion of the container end as shown in Fig. 5, and showing the lever opener applied for rupturing the metal, and

55 Fig. 7 is a view showing a slightly further modified form of the invention wherein the thinned

portion is concentric to the center of the end and disposed adjacent the double seam.

The invention has to do with a container which is made from sheet metal. A sheet metal blank is cut to proper shape and then is formed into a body for the container. The edge portions of the blank are joined by the usual side seam. The body is flanged and a bottom end is secured thereto by double seaming. In the drawings, two forms of containers are shown, one of which is particularly adapted for beverages. In the container for beverages, the blank forming the top end is shaped so as to provide a nozzle. The metal at the upper end of the nozzle is formed with a depression. This depression is surrounded with a side wall, 15 the lower portion of which is substantially at right angles to the bottom wall of the depression. The metal is thinned at the angle between the side wall and the bottom wall of the depression. This is done by die pressure applied to the inner 20 surface of the bottom wall adjacent the angle so as to draw the metal at the angle and thus provide a thinned section joining the vertical wall of the depression with the bottom wall. When the metal is thinned in this particular region and in 25 the manner stated, external pressure applied to the bottom wall adjacent the side wall will place the thinned section under tension and will cause the same to be stretched and finally ruptured. However, internal pressure against the bottom 30 wall will produce a compression strain upon the thinned section, wherein the lines of force are within the metal in the side wall and no rupturing takes place.

In the form of the invention shown in other 35 figures of the drawings, the can top which is seamed to the can body is the ordinary flat top, and said top is shaped so as to provide a side wall surrounding a depressed portion, and the metal is similarly thinned at the angle between 40 this side wall and the bottom wall of the depression.

Referring more in detail to the drawings, the improved easy opening container, as shown in Figures 1 to 4, includes a body portion 1 formed 45 from a sheet metal blank, the edge portions of which are joined by an ordinary seam indicated at 2. The bottom end 2a of the container is drawn from a metal blank and secured to the body portion in the usual way by double-seaming. 50 The container body and the bottom end are preferably made from tin plate which is enameled and baked in the flat. After the body is formed and the end attached thereto, a second coating of enamel may be applied so as to cover the solder-

bonded side seam. The enamel coating is only used to prevent the contents of the can from contacting with the metal, and if the metal has no injurious effect upon the contents which is to be placed in the can, then it is not necessary to apply a second coating of enamel, or even enamel the sheets in the flat. The invention is not directed to the particular way in which the inner surface of the container is treated, but rather to the construction of the container whereby it may be of few parts and easily opened. Instead of attaching the can top 3 to the body 1 by a double seam, the can top and body may all be drawn from a single piece of metal and the number of parts 15 further reduced while still providing a container that may be easily opened.

As shown in Fig. 1, the top end 3 is secured to the body portion 1 by a double-seam 4. This top end has a depressed raised portion terminating 20 in a nozzle 5. At the upper end, the metal is shaped so as to provide a curved lip 6 and a shoulder 7 which curves upwardly slightly at its inner edge. The purpose of this shoulder will be stated later. The can top is drawn from a single sheet metal blank and the outer end of the nozzle is closed by metal which forms an integral part of the can top. The outer end of the nozzle is provided with a depression 8 forming a side wall 9 which extends substantially at right angles 25 to the bottom wall 10 where it joins said bottom wall. This wall 9 curves outwardly into the lip 6.

After the metal is formed with this depression 8 and the side wall arranged at right angles to the bottom wall 10, then the metal is subjected 30 to die drawing in the region of the angle between said side wall and the bottom wall. This die drawing action thins the metal at the angle. The thinnest section of the metal after this die drawing action lies in a line at substantially forty-five degrees to the vertical wall and the bottom wall and midway between the two. While it is preferred to thin the metal at the angle so that the inner surface lies in the line $a-b$, it will be understood that the metal may be otherwise 40 shaped at this angular portion between the side wall and the bottom wall of the depression, but it is essential that the thinning of the metal shall take place substantially in that portion of the metal which joins the side wall to the bottom wall. The method of thinning the metal is described and claimed in my co-pending application Serial No. 122,852, filed of even date herewith:

The container is opened by pressure applied 55 externally to the bottom wall of the depression. This may be done by any suitable tool, but a lever opener such as indicated at 11 is preferred. The lever opener has a depending arm 12 which is shaped so as to extend beneath the shoulder 7. 60 The inner face of this arm is curved to conform to the curvature of the shoulder, and the shoulder is curved upwardly at its inner portion so that the lever opener will be firmly engaged with the can top during the opening of the same. The 65 lever opener is shaped so as to provide a projecting arm 13 which is adapted to contact with the bottom wall of the depression at a point substantially opposite where the lever opener engages the shoulder 7. The lever opener has a handle 70 end 14 and when this handle end is raised, then the lever opener fulcruming on the shoulder will apply pressure against the bottom wall of the depression very close to the thinned portion. Fig. 3 shows in broken lines the condition of the 75 metal parts after pressure has been applied

through this lever opener almost to the point of rupturing the metal. It will be noted that the bottom wall has been depressed and the thinned portion moved downward until it is almost in line with the side wall. In full lines in Fig. 3, the metal is shown as ruptured through a continued pressure of the lever opener against the bottom wall. The section 9a of the thinned portion remaining intact with the side wall is positioned in alinement with the side wall 9 so that the raw edge of metal incident to the rupturing of the same faces substantially downward. After the metal has been ruptured at the starting point, a further movement of the lever opener will cause the metal to rupture along a line determined by the thinned portion at the angle. The lower edge 15 of the lever opener terminates at a point 16 which is a short distance away from the vertical wall 9, and as a result, the metal will be ruptured along the thinned line throughout the greater extent thereof, but a sufficient portion will be retained intact to form a hinge and support the section which is torn away. This is of advantage in connection particularly with a container for a beverage, as it retains the ruptured metal within the container when the container is inverted for pouring the contents through the opening formed.

While the metal can be readily ruptured through the aid of a suitable tool, when pressure is applied externally to the bottom wall, it will not be ruptured by a similar pressure or a greater pressure applied internally against the bottom wall. If the container is used for the packaging of beer, it is necessary to process the beer after the container is sealed, and during this treatment of the beer, an internal pressure develops which is substantially ninety pounds per square inch. There is also a considerable internal pressure on all carbonated beverages, and on all highly volatile products. When the internal pressure against the bottom wall of the depression exceeds the external pressure thereagainst, there are forces of compression exerted on the thinned section, which forces lie within and restrained by the metal in the side wall, and therefore, the metal will not be ruptured. Applicant has, therefore, provided an easy opening container wherein the metal is thinned, but thinned in such relation to the wall which contains the thinned portion that external pressure can be used for easily rupturing the metal, while internal pressure will not rupture the metal.

When the thinned portion is located at the angle between the side wall of the depression and the bottom wall thereof, a relatively wide opening will be produced through which the contents may be poured. Furthermore, the metal is ruptured at a point well away from the lip 6, and the torn edge faces inwardly so that there is no danger of the operator contacting with this raw edge, and the container is one wherein the nozzle can be placed in the mouth for drinking the contents.

In Figures 5 and 6 of the drawings, the invention is shown as applied to what is often referred to as an open top container. The container consists of the usual body portion 17 to which a closure end 18 is secured by a double-seam 19. This closure end is die-shaped from a single piece of metal and is provided with a depression 20 surrounded by a side wall 21 which is very shallow so that the bottom wall is offset only a short distance from the plane of the end 18. The metal at the angle 22 between the side wall 21 and the bottom wall 20 is drawn and thinned in the same

manner as in the construction shown in Figures 1 to 4. The lever opener indicated at 23 is provided with an arm 24 which hooks under the double seam joining the can top to the body wall.

- 5 The arm 25 of the lever opener is adapted to bear on the bottom wall of the depression adjacent the side wall and will rupture the metal in the manner above described. The double seam has a shoulder adjacent the thinned section of metal 10 with which the lever opener cooperates. This depressed section may be made relatively small when a container is intended for packaging liquids, and again it may be relatively large so that a spoon may be inserted therethrough for the 15 removing of the contents of the container.

In Fig. 7 there is a further modified form of construction for the open top container. The body portion 17 has an end 26 secured thereto by a double seam 27. This container end is 20 shaped so as to provide an annular upwardly and inwardly extending portion 28 integrally joined to a central raised portion. The raised portion is depressed so as to form a recess 29 surrounded by a side wall 30. The bottom wall 31 of this depression is substantially at right angles to the lower portion of the side wall 30, and the metal at the angle is drawn and thinned in the same manner as described in connection with Figures 1 to 6. In this form of the invention, a lever 25 opener 32 is used in the manner illustrated in Fig. 7. The lever opener has an arm 33 which engages beneath the shoulder at the double seam, and a portion 35 which is shaped so as to bear against the bottom wall of the depression at the 30 point nearest where the arm 33 contacts with the double seam. The swinging of the lever opener will cause the metal to be ruptured and then the lever opener is moved along the double seam to another set position and again pressed 35 against the bottom of the depression and by shifting the lever opener all the way around the can top, the bottom wall of the depression may in part, or in whole, be separated from the can top for the opening of the container.

40 It will be noted that in each instance illustrated, the thinning of the metal takes place at the angle joining the lower portion of the side wall surrounding the depression with the bottom wall of the depression, and therefore, when pressure is applied against the bottom wall, tension 45 forces will be created within the thinned portion and said thinned portion will be pulled substantially into alignment with the side wall and finally ruptured. However, any internal pressure 50 against the bottom wall of the depression will create compression forces within the thinned portion which lie within the metal and are restrained by the side wall so that no rupturing of the metal 55 occurs.

60 It is apparent from the above that an easy opening container has been provided wherein the metal may be readily ruptured by external pressure, but internal pressure will not rupture the metal. The container, can therefore, be used for 65 various forms of products and beverages, such as carbonated beverages and beverages which are pasteurized after being sealed in a container. Then again, the weakening line may be reduced to a minimum for easy opening with the assurance that any pressure from within will not rupture the metal.

In the usual form of scoring metal, a die is used which cuts into the metal and this severs the enamel coating exposing often the metal core. 70 It would not be practical to score the container

on its inner surface if it is to be used for a product wherein contact of the product with the metal has a deleterious effect thereon.

While it is preferred to form the can top with a closure member which may be ruptured all 5 from one integral piece of metal, it will be understood that from certain aspects of the invention, the closure member may be separate and attached to the can top. It is essential, however, that the closure member shall have a depression formed therein providing a side wall, the lower portion of which is substantially at right angles to the bottom wall, and that the metal shall be thinned at the angle between the side wall and the bottom wall so that it can be ruptured by external pressure, while internal pressure will not rupture the same. It is also obvious that the invention may be applied to various forms of containers and may be modified as to details of construction without departing from 10 the spirit of the invention as set forth in the appended claims. 15

Having thus described the invention, what I claim as new and desire to secure by Letters Patent, is—

25 1. An easy opening sheet metal pressure container comprising a body, top and bottom ends hermetically joined thereto, said top having a depression formed therein surrounded by a side wall, the lower portion of which is substantially at right angles to the plane of the bottom wall of the depression, the metal at the angle between the side wall and the bottom wall being shaped so as to provide a thinned portion with the maximum extent of thinness lying midway between 30 the side wall and the bottom wall whereby external pressure applied to the bottom wall at a point adjacent the side wall will create within said thinned portion, tension forces which will rupture the same, and internal pressure applied to 35 the bottom wall will create compression forces within said thinned portion which will be restrained by the vertical wall and the rupturing of the metal prevented.

40 2. A sheet metal pressure container comprising a body, top and bottom ends hermetically joined thereto, said top end being provided with a raised nozzle having the end thereof closed, said top end, nozzle and closure therefor being of one integral piece of metal, the closed end of 45 said nozzle being provided with a central depression surrounded by a side wall, the lower portion of which is substantially at right angles to the bottom wall of the depression, the metal at the angle between the side wall and the bottom wall 50 being shaped so as to provide a thinned portion with the maximum extent of thinness lying midway between the side wall and the bottom wall whereby external pressure applied to the bottom wall at a point adjacent the side wall will create 55 within said thinned portion, tension forces which will rupture the same, and internal pressure applied to the bottom wall will create compression forces within said thinned portion which will be restrained by the vertical wall and the rupturing of the metal prevented.

60 3. A sheet metal pressure container comprising a body, top and bottom ends hermetically joined thereto, said top end being provided with a raised nozzle having the end thereof closed, said 65 top end, nozzle and closure therefor being of one integral piece of metal, the closed end of said nozzle being provided with a central depression surrounded by a side wall, the lower portion of which is substantially at right angles to the bottom wall 70 75

of the depression, the metal at the angle between the side wall and the bottom wall being thinned and disposed so that external pressure applied to the bottom wall at a point adjacent the side wall will create within the thinned portion, tension forces which will rupture the same, said nozzle between the side wall of the depression and the outer wall of the nozzle being rounded so as

to form a smooth pouring lip, and a shoulder overhanging the outer wall of the nozzle, which shoulder is curved upwardly on its under face so as to permit the engagement of a lever opener therewith for applying pressure to the bottom wall of the depression for the rupturing of the metal.

5 WILLIAM F. PUNTE.
